F. G. Fischer,
ATTORNEY.

UNITED STATES PATENT OFFICE.

HERBERT LEGGETT, OF KANSAS CITY, MISSOURI.

SOUND-MODIFIER.

1,384,964.

Specification of Letters Patent. Patented July 19, 1921.

Application filed April 13, 1920. Serial No. 373,654.

To all whom it may concern:

Be it known that I, HERBERT LEGGETT, a citizen of the United States, residing at Kansas City, in the county of Jackson and State of Missouri, have invented certain new and useful Improvements in Sound-Modifiers, of which the following is a specification.

My invention relates to new and useful improvements in sound modifiers for internal combustion engines, and my object is to produce a simple, durable and efficient device of this character for modifying the harsh sound of the exhaust gases and converting such sound into harmonious tones without creating back pressure to affect the power of the engine.

In order that the invention may be fully understood, reference will now be had to the accompanying drawing, in which:

Figure 1 is a central longitudinal sectional view of the device.

Fig. 2 is a cross section on line II—II of Fig. 1.

Fig. 3 is a central longitudinal section of a modified form of the device.

Fig. 4 is a detail of a modified form of sound modifier.

Fig. 5 is a detail of another modified form of sound modifier.

In carrying out the invention, I employ a tubular shell 2 closed at its ends by heads 4 and 6 provided with flanges 8 and 10, respectively, which fit snugly within the ends of the shell 2. The head 4 is of conical form and has an axially disposed tubular duct 12 connected at its outer end to the exhaust pipe A of the gas engine (not shown) and provided with equally disposed peripheral ports 14 through which the pulsating exhaust gases are equally distributed in the shell 2, to the end that the pressure in said shell may be more uniform than if said exhaust gases entered through a single side port. The inner end of the duct 12 is closed as indicated at 16 and has a threaded bore to receive the correspondingly threaded end of a tie-rod 18, extending axially through the shell 2 and out through an outlet duct 20 in the head 6, where its threaded end is provided with a nut 22 which coacts with said tie-rod 18 in drawing the heads 4 and 6 firmly against the respective ends of the shell 2.

Before threading the tie-rod 18 into the closed end 16 of the duct 12, said tie-rod is

equipped with one or more bell-shaped sound modifiers. In Fig. 1 of the drawings I have shown sound modifiers 24 and 25, the reduced ends 26 and 28 of which are directed toward the inlet duct 12 and threaded upon the tie-rod 18 where they are securely locked by jamb nuts 30 and 32, respectively. The forward sound modifier 24 is positioned to abut the closed end 16 of the duct 12 when the tie-rod 18 is threaded into said closed end 16. By thus securing the sound modifiers 24 and 25 at their reduced closed ends only, their enlarged free ends or mouths are free to vibrate and their tendency to vibrate is increased by tapering the metal in their conical walls toward their enlarged ends as shown on Fig. 1.

In practice, it will be seen that this device can be readily applied to the exhaust pipe of an explosive engine and as the exhaust gases enter the shell 2 they first impinge against the outer surface of the sound modifier 24 in their passage to the restricted annular passageway 36 between the mouth of said sound modifier 24 and the shell 2. As the exhaust gases pass through the annular passageway 36 they tend to combine and in so doing, impinge against the conical wall of the second sound modifier 25 which directs the gases to the restricted annular passageway 38 between the mouth of said modifier 25 and the shell 2. After passing through the passageway 38 the exhaust gases escape to atmosphere through the outlet duct 20. As the exhaust gases impinge against the outer surfaces of the sound modifiers 24 and 25, as above stated, the sound waves occasioned thereby with their harsh tones are greatly reduced in volume as indicated by the irregular lines a, while harmonious tones are produced within said modifiers 24 and 25 which increase in volume as indicated by the irregular lines b, and thus completely nullify the harsh tones aforementioned.

The device disclosed by Fig. 3, is similar to the form disclosed by Fig. 1, as evidenced by similar reference characters with exponents "a," the only difference being that but one sounding member 24^a is employed instead of two.

The sounding member 24^b, Fig. 4, has longitudinal slits 40 and the sounding member 24^c, Fig. 5, has perforations 42 and marginal notches 44 to give different tones from each other and the members 24 and 25.

While I have shown sound modifiers of

conical form I do not restrict myself to this particular shape for experience has shown that modifications of different forms, thicknesses and materials produce different results, and variety of tone may be had by providing the modifiers with slits, perforations, notches, etc. In all cases, the sounding member is suspended from a point near the center and its outer edge is left free to vibrate.

It will thus be seen that I have made new and useful improvements in the articles described and, what I claim as new and desire to secure by Letters Patent, is:

1. In a device of the character described, a shell, heads removably secured to the ends of said shell and provided respectively with inlet and outlet ports for the passage of exhaust gases, a conical sound modifier arranged within the shell and supported at its reduced end only leaving its enlarged end free to vibrate from impact of the exhaust gases passing through the shell.

2. In a device of the character described, a shell, heads removably secured to the ends of said shell, an inlet duct to one of said heads having a closed inner end and equally-spaced peripheral ports for the passage of exhaust gases into the shell, an outlet duct in the companion head for the escape of the exhaust gases, and a conical sound modifier arranged within the shell and supported at its reduced end only leaving its enlarged end free to vibrate from impact of the exhaust gases passing through the shell.

3. In a device of the character described,

a shell, heads removably secured to the ends of said shell and provided respectively with inlet and outlet ports for the passage of exhaust gases, a sound modifier within the shell and having a conical wall tapering in thickness toward its enlarged end, and a tie-rod extending axially through the shell to secure the heads and said sound modifier in place.

4. In a device of the character described, a shell, heads removably secured to the ends of said shell and provided respectively with inlet and outlet ports for the passage of exhaust gases, a tie-rod extending axially through the shell and said heads to secure them in assembled position, and a plurality of conical sound modifiers within the shell mounted at their reduced ends upon said tie-rods and having their enlarged ends free to vibrate from impact of the exhaust gases passing through the shell.

5. In a device of the character described, a tubular shell, heads at the ends of said shell and provided respectively with inlet and outlet ports, bell-shaped sound modifiers axially disposed within the shell and supported at their reduced ends only which are directed toward the inlet port, substantially as shown and described.

In testimony whereof I affix my signature in the presence of two witnesses.

HERBERT LEGGETT.
